UNITED STATES PATENT OFFICE.

RUFUS K. TELLER, OF UNADILLA, NEW YORK.

DESIGN FOR A KITCHEN-KNIFE.

43,729.

Specification for Design.

Patented Mar. 18, 1913.

Application filed October 7, 1912. Serial No. 724,484. Term of patent 7 years.

To all whom it may concern:

Be it known that I, RUFUS K. TELLER, a citizen of the United States, residing at Unadilla, in the county of Otsego and State of New York, have invented a new, original, and ornamental Design for a Kitchen-Knife, of which the following is a specification, reference being had to the accompanying drawing, forming a part thereof.

In the drawing, Figure 1 is a side view of

a utensil embodying my invention; and Fig. 2 is an edge view of the utensil.

I claim:

The ornamental design shown in the drawing for a kitchen knife.

RUFUS K. TELLER.

Witnesses:

W.M. H. HILT,
CHARLES C. FLOYD.
